(57) CLAIM

The ornamental design for a squirting toy with handles, as shown and described.

DESCRIPTION

FIG. 1 is a perspective view of a squirting toy with handles showing my new design;

FIG. 2 is a left side view thereof;

FIG. 3 is a front view thereof; and,

FIG. 4 is a rear view thereof.

The broken lines are for illustrative purposes only and form no part of the claimed design.

1 Claim, 2 Drawing Sheets

FIG. 3
